UNITED STATES PATENT OFFICE.

EMIL GOTTFRIED JOHANSON, OF ROCKFORD, ILLINOIS.

ELECTRICALLY-OPERATED CUTTER.

1,198,923.

Specification of Letters Patent. Patented Sept. 19, 1916.

Application filed October 25, 1913. Serial No. 797,245.

To all whom it may concern:

Be it known that I, EMIL GOTTFRIED JOHANSON, a citizen of the United States, and resident of Rockford, in the county of Winnebago and State of Illinois, have invented 5 certain new and useful Improvements in Electrically-Operated Cutters, of which the following is a specification.

My present invention relates in general 10 to cutter devices, and more particularly mechanically operated devices for cutting sheets, and has special reference to the provision of an improved cutter of the reciprocating type.

15 The principal objects of my present invention are the provision of an improved cutter of the class referred to, characterized by the employment of a simple form of electro-magnetic operating means for imparting the reciprocatory motion to the cutter; the provision of an improved form of electrically operated cutter employing a simple form of controlling switch for the electro-magnetic operating means; the provision of an improved form of cutting mechanism for cutters; and generally to improve and cheapen 20 the cost of cutters of the nature referred to, together with such other objects as may hereinafter appear.

25 In attaining the foregoing objects I have provided a construction, a preferred embodiment of which is illustrated in the accompanying drawing, wherein—

30 Figure 1 is a side elevational view of a cutter embodying my present improvements; Fig. 2 is a plan view thereof; and Fig. 3 is a sectional under-plan view taken on the line 3—3 of Fig. 1.

35 Referring now more particularly to Fig. 1 of the drawing, it will be observed that I have here illustrated an embodiment of my improved cutter in the portable form designed for use by garment makers in the cutting of single thicknesses of cloth, though 40 obviously my present improvements are susceptible of a wide range of usefulness by a suitable modification in the sizes of the various parts.

45 In the construction shown in the drawing I employ a base 10 which is preferably made of insulating material highly polished and shaped to slide easily on the cutting table, mounting upon said base a frame including members 12 within which are disposed a pair 50 of magnet coils 14, 14, joined together in se-

ries in the customary manner as indicated at 15. The coils 14—14 are provided with the usual contact points 16, 16, against which the armature 17 is adapted to bear, such armature 17 being flexibly hinged to the frame 60 member 12 by the strap of flexible spring metal indicated at 18, which strap acts as an interrupter and is continued to form a contact at 19 with the contact member employed in connection with the binding post 20. 65 The hinge connection just referred to is, as will be seen on inspection of the drawings, transverse to the cutting edges of the knives shortly to be described.

70 On the base 10 I mount a stationary knife 21 having an inclined and chamfered cutting edge as indicated at 22 and disposed opposite to said knife 21 is a knife 23 having an oppositely inclined and chamfered cutting edge 24. The knife 23 is preferably disposed in a guide slot indicated at 25 (Fig. 3) in a lateral extension 26 of a supporting member 27 which is attached to the frame 12 as indicated at 28, the shank 29 of said knife 23 being pivoted at 30 to an extension 80 31 of the armature 17.

85 A handle 32 is employed for moving the device about, and at 33 is indicated a contact button having an insulated covering. The contact button 33 is carried on a spring strip 34 which is connected by a conductor 38 from one of the coils 14, the conductor 39 of the other coil 14 being fed from a suitable source of electric current supply (not shown), and the opposite pole of said 90 source of supply being connected by a conductor 40 to a contact point 43 on the strip 18, a conductor 44 being used to connect the binding post 20 and the contact post 41 (Fig. 2) opposite said contact 33 and insulated therefrom.

100 In the operation of cutters embodying my present improvements, the handle 32 is grasped and the cutter moved to the desired position relatively to the sheet of material to be cut, indicated diagrammatically at 42, and the button 33 pressed into contact with the point 41, thereby completing the circuit between the conductors 39 and 40 and exciting the magnet coils 14, 14, 105 which in turn vibrate the armature 17, carrying the extension 31 to which the knife shank 29 is pivoted, thus causing rapid reciprocation of the blade 23 relatively to the blade 21.

When the button 33 is depressed, the electric circuit is completed as follows, viz.: conductor 40, point 43, interrupter spring 18, contact, 19, conductor, 44, spring 34, contact, 41, conductor, 38, through coils, 14—14, (which are connected by conductor, 15,) and conductor, 39, to a source of power, (not shown,) thus energizing the coils, 14—14, and causing the armature, 17, to be attracted thereto, thereby opening the circuit at 19, and thus deenergizing said coils, 14—14, which permits the raising of the armature, 17, by means of the spring, 18, thereby restoring the circuit just described, when the operation is repeated.

Having thus described my invention and illustrated its use, what I claim as new and desire to secure by Letters Patent is:

1. A cutter device of the character described comprising, in combination, a base, a cutter member on said base adjacent one side of said base, means for operating said cutter adjacent the other side of said base,
- 20

and a handle substantially vertically over said cutter. 25

2. A cutter device of the character described, comprising, in combination, a base, a pair of oppositely disposed cutter members in operative relation, mounted on said base, adjacent one end thereof, means for producing reciprocatory movement of one of said cutters, relatively to the other adjacent the other end of said base, and a handle of greater length than width or height, mounted on said base, substantially parallel thereto, with its mid-point substantially vertically over the point of engagement of said cutters with the other. 30

In testimony whereof I have hereunto signed my name in the presence of the two 40
subscribed witnesses.

EMIL GOTTFRIED JOHANSON.
